UNITED STATES PATENT OFFICE

2,463,242

COATED ABRASIVE ARTICLE

Richard Paul Carlton, St. Paul, Minn., assignor,
by mesne assignments, to Behr-Manning Corporation, Troy, N. Y., a corporation of Massachusetts

Application July 8, 1941, Serial No. 401,484, now Patent No. 2,376,342, dated May 22, 1945, which is a division of application Serial No. 422,065, January 20, 1930, now Patent No. 2,318,570, dated May 4, 1943. Divided and this application May 21, 1945, Serial No. 594,824

1 Claim. (Cl. 51—185)

1

This invention relates in general to coated articles and to the art of coating, and more particularly to an improved method of and apparatus for applying pulverulent coatings to suitably adhesively coated surfaces, and while the invention finds particular utility in the art of making flexible abrasives, and is, therefore, described and illustrated for this purpose, it finds a wide field of utility for analogous purposes.

This application is a division of my copending application Serial No. 401,484, filed July 8, 1941, now Patent No. 2,376,342, granted May 22, 1945, as a division of my application Serial Number 422,065, filed January 20, 1930, now Patent No. 2,318,570, granted May 4, 1943.

It is well known that in the art of making sandpaper, emery paper or cloth and similar abrasive articles, a flexible or in some cases, a rigid, backing of paper, cloth, wood or the like is employed, to which is applied a coating of an adhesive substance, such as animal or vegetable glue, or where a waterproof article is desired, the backing may be coated with any of the now well known waterproof adhesives for this purpose, and while the coating is still wet or unset, a suitable abrasive material such as garnet, corundum, sand or the like is applied thereto. The grains of abrasive substances are usually applied by gravity upon the upper adhesive coated surface of the backing, and they lie in the adhesive material in haphazard fashion due to the elongated nature of the abrasive particles, and in a large degree, the facets or cutting edges of the individual grains or grits often lie flat upon or are embedded in the adhesive coating in such a manner that in some instances their best cutting edges never come into contact with the work or at best are brought inefficiently into contact therewith. The invention here has as one of its objects to measurably increase the number of grits whose longer or greater dimensions are perpendicular to the surface of the backing, thereby to present more efficiently the cutting edges to the work, and increase the cutting ability and life of the abrasive article.

The principal objects and advantages of this invention reside in the provision of an improved abrasive coated article, such, for example, as sandpaper, emery cloth, or the like, wherein the abrasive grits or grains lie in position on the backing for increasing the cutting effect and durability of the abrasive article; the provision of an improved abrasive article wherein the abrasive grits are disposed so that their cutting facets are presented in position to more efficiently en-

gage the work and thereby produce a sharper article; and the provision of an improved abrasive article wherein the abrasive grains or grits are applied thereto with their longer or greater dimension substantially perpendicular to the plane of the backing.

This invention further includes as objects and advantages thereof, the provision of an improved method of and apparatus for manufacturing abrasive articles; and the provision of an improved method of and apparatus for causing the articles of pulverulent material to impinge upon and assume a position in the adhesive coated surface substantially normal or perpendicular to the surface of the backing.

The foregoing and such other objects and advantages as may appear or be pointed out as this description proceeds are attained in the structure illustrated in the accompanying drawing.

The method of the present invention includes as steps thereof the feeding of a web or strip of paper or other fabric at a predetermined rate of speed, applying an adhesive substance to the under side of the sheet, or applying the adhesive coating to one side and then moving the sheet with the coated side out, and simultaneously with the movement of the coated sheet, causing a grit or abrasive material to be applied to this side.

In my original application Serial No. 422,065, filed January 20, 1930, and in my copending application Serial No. 401,484, filed July 8, 1941, as a division of said original application Serial No. 422,065, I disclosed in the specifications and drawings thereof various different forms of apparatus and methods for depositing the abrasive grains in the adhesive coating on the backing with their major axes substantially perpendicular to the surface of the backing. These disclosures included various means of propelling the abrasive particles through an intervening space by mechanical or electrical force as well as the apparatus and method here disclosed for causing the abrasive particles to assume an erect position on a carrier surface and then bringing the particles while so positioned into embedding contact with the adhesive coating on the backing sheet. This latter method not only effects the desired positioning of the abrasive grains substantially perpendicular to the backing but also results in the positioning of the particles with their outer ends in a surface determined by the surface of the carrier surface from which they are transferred to the adhesive coating of the

backing, thus producing an improved coated abrasive sheet.

Referring now to the drawing, the flexible backing 108 of paper or cloth or other fabric is trained over a series of rollers 104, 104, and around the upper one of a pair of squeeze rollers indicated at 107, the lower one of said pair being in contact with adhesive material contained in a tray or tank 105 whereby an adhesive coating is applied to one side of the moving web.

The moving web thus adhesively coated is carried over a roller 108, thence over a roller 109, said roller 109 being mounted on a shaft carried in a bearing arm or arms 110 pivotally mounted at 111, whereby the roller 109 may be raised and lowered in the substantially vertical plane of the arrows 112, thus permitting the lower flight 113 of the paper web to be elevated or depressed, as the case may be.

Mineral is deposited from a hopper 114 onto a conveyor 115 trained over rollers 116 and 116a, the upper flight 117 of said conveyor passing beneath the roller 109 and the moving web and conveying mineral, that is, the grit, to a point adjacent to the roller 109.

Preferrably immediately below the axis of the roller 109 and below the upper flight 117 of the conveyor 115, I provide an electro-magnet 118 which is so mounted that its magnetic flux passes through the conveyor and causes the mineral particles to stand erect, as indicated at 119, as they move along with the upper flight of the conveyor. While the mineral particles are thus standing erect they come into contact with the adhesively coated side of the paper backing and are thus picked up by it and conveyed away, the backing being trained over rollers 120 and carried to festoons for drying. It will be observed that the angularity of the lower stretch 113 of the paper web is such that it lies upwardly to the conveyor 115. In this way the particles of grit adhering to the paper are not knocked down by other particles remaining on the conveyor, it being understood that the grit is fed somewhat in excess of the required amount so that an adequate amount will be deposited on the adhesively coated side of the backing. The excess mineral drops off the conveyor 117 and is carried to a collecting means by a conveyor 121.

It may be desirable that a certain amount of 50

pressure be exerted on the erect particles of mineral so as to cause them to impinge upon the adhesively coated side of the paper.

By manipulation of the arms 110, an adjustment of the pressure of the roller 109 may be attained.

It will be understood that by varying the amount of mineral fed from the hopper, the strength of the electro-magnet, that is, the strength of the flow current transferred, and the position of adjustment of the roller 109 the assembly may all be properly correlated for obtaining the desired grade of finished article. Since the abrasive particles are supported upon the surface of the conveyor belt any variation in the longer dimensions of the particles will affect the depth to which they become embedded in the adhesive coating but the relative position of the ends resting on the conveyor belt will be determined by the surface of the belt which is ordinarily a smooth plane.

Having thus described my invention, what I claim as new and desire to secure by Letters Patent is:

An abrasive sheet material comprising a backing and a layer of abrasive particles of various sizes and shapes bonded thereto by an adhesive binder coat, all of said abrasive particles having their major axes parallel and perpendicular to the plane of the backing and having their exposed ends lying in a common plane parallel to the plane of the backing.
